United States Patent Office.

ELI THAYER, OF NEW YORK, N. Y.

Letters Patent No. 61,118, dated January 8, 1867.

IMPROVED BELT-COUPING.

The Schedule referred to in these Letters Patent and making part of the same.

TO ALL WHOM IT MAY CONCERN:

Be it known that I, ELI THAYER, of the city, county, and State of New York, have invented a new and improved Method of Fastening Belts; and I do hereby declare that the following is a full and exact description of my invention, reference being had to the accompanying drawings, and to the letters of reference marked thereon.

The nature of my invention consists in so constructing a clasp and key that when the ends of the belt are passed through the clasp they are firmly held in their place by a key or wedge placed between that portion of them surrounded by the clasp.

To enable others skilled in the art to make and use my invention, I proceed to give a full description of its construction and mode of operation.

Figure 1 represents the clasp or band through which the ends of the belt are passed.

Figure 2 represents the key or wedge to be placed between the ends of the belt and partly or wholly within the clasp.

Figure 3 represents a vertical section between the two ends of the clasp, of the clasp key, and belt.

The clasp is made of metal, and of weight according to the size or width of the belt to which it is to be applied, being about one ounce for every inch in the width of the belt. The space between the sides of the clasp should be sufficient to allow the ends of the belt to be passed through them easily. The lower face of the clasp, as shown in fig. 1, is surrounded by or widened into a flange, for the purpose of giving it strength, while the upper face, as seen in the same figure, shows the sides diminished in thickness to a knife edge by the outer and inner bevel. The key is of such length and thickness as to allow it to pass through the clasp parallel with the sides of the same. The angles made by the sides of the key with each other must be determined by the angle made by the inner surfaces of the sides of the clasp with each other. The key may be made of metal, wood, leather, or other suitable substance, or may be one or both ends of the belt bent over and turned inward, so as to act as a wedge or fastener.

From the figures of the accompanying drawings, and from the above description, it will be readily seen that when the ends of the belt are inserted in or passed through the clasp, as shown in fig. 3, and the key inserted between them, they will be held firmly in their place, and more firmly in proportion to the power applied to draw the key into or through the clasp. This method of fastening belts will be of great use in factories and machine shops, since in this way a slack belt can be tightened in one minute, while by the ordinary method of lacing or hooks the same work would require an hour. The belt fastened in this way is entire and uninjured, while by the other methods it is weakened by numerous holes. The length of the clasps used should be a little less than the width of the belts, so that they may pass over cone pulleys and through "shippers" without coming in contact with them.

Having now described its construction and mode of operation, what I claim as my invention, and desire to secure by Letters Patent, is—

The key, as shown in fig. 2, in combination with the clasp and belt, as shown in figs. 1 and 3.

ELI THAYER.
